FOLLOW-UP SYSTEM

Howard A. Satterlee, Dayton, Ohio, assignor to
 Submarine Signal Company, Boston, Mass., a
 corporation of Maine

Application December 23, 1940, Serial No. 371,331

10 Claims. (Cl. 172—239)

The present invention relates to follow-up systems.

Various arrangements have heretofore been proposed for the purpose of causing a remote object to take up a predetermined position in response to the setting of a control indicator to a corresponding position by an operator at a control station. Among the difficulties which arise in such systems are the difficulties of reducing to a minimum the time lag between the setting of the control indicator and the corresponding motion of the remote object, the elimination of hunting and the obtaining of sufficient accuracy in the final position of the remote object. It is an object of the present invention to provide a follow-up system which will provide accurate and close coupling of the remote object with the control device, without hunting and which moreover will have the desirable characteristics of simplicity and reliability.

This and other objects of my invention will best be understood from the following description, taken in connection with the accompanying drawing which schematically illustrates the invention.

As indicated in the drawing, the driving motor 1 which may be geared or otherwise connected to the remote object is preferably of the direct current type having a commutator type armature 2 and a field winding 3 separately excited from a source of direct current. Two grid controlled rectifiers of the gaseous electron discharge type 4 and 5 provide the armature operating current. Anode potential for the two tubes is provided by a transformer 6 having a primary winding 7 connected to a source of alternating current and two secondary windings 8 and 9. The secondary winding 8 is connected by one end to the anode 11 of tube 4 and by the other end through conductors 12 and 16 to the armature 2 and from the latter by conductor 17 to the cathode 14 of tube 4. The secondary winding 9 is connected by one end to the anode 15 of the tube 5 and by the other end by conductors 18 and 17 to the armature 2 and thence by conductor 16 to the cathode 19 of tube 5. The grids 20 and 21 of the two tubes are respectively connected through current-limiting resistors 22 and 23 to the movable contacts 28 and 29 of potentiometers 32 and 33 and through the potentiometers to the extremities 30 and 31 of a center-tapped resistor 24. The motor armature 2 is shunted by a center-tapped resistor 13, the center tap of which is connected through a biasing battery 25 to the center tap of the resistor

24. High frequency by-pass condensers 26 and 27 are also provided between the cathodes and grids of the tubes 4 and 5, respectively.

The potentiometer 32 is connected across a source of alternating current of the same frequency as that which supplies the anodes of the rectifiers 4 and 5 but of a phase angle lagging the potential of anode 11 by approximately 90°. Similarly, the potentiometer 33 is connected across a source of alternating potential of the same frequency as that supplying the anode circuits of the tubes but of a phase angle lagging the potential of anode 15 by approximately 90°. The magnitudes of the two alternating potentials thus introduced into the grid circuits of the rectifiers are adjusted to be of a very small value, depending upon the characteristics of the gaseous discharge tubes 4 and 5. The maximum values of these alternating grid potentials may, for example, be of the order of the magnitude of the maximum negative potential of the critical grid voltage curve for the tubes in question at the anode voltage used. The critical grid voltage curve is to be understood as the graph of the grid-to-cathode voltage which is just sufficient to initiate conduction through the tube at each instant in the positive half cycle of the anode potential.

It will be understood, of course, that the type 30 of tubes referred to is that in which when conduction has once been started, it will continue until the anode potential reverses its polarity, the grid having control only prior to the time conduction commences in any particular positive half cycle of anode potential.

The grid circuit of tube 4 may thus be traced from the grid 20 through the resistor 27 the potentiometer 32, the upper half of resistor 24, the biasing battery 25 and the upper half of 40 resistor 13 to the cathode 14. Similarly, the grid circuit of tube 5 may be traced from the grid 21 through the resistor 23, the potentiometer 33, the lower half of resistor 24, the biasing battery 25 and the lower half of resistor 13 to cathode 19.

A control potential for the grids of the tubes is impressed across resistor 24. The circuit for producing the grid control voltage which is to be impressed across resistor 24 will be described 50 subsequently.

It is convenient at the present time to consider the operation of the grid controlled rectifier circuit which has so far been described. Considering, first, the tube 4, it will be noted that 55 the anode circuit of the tube contains a source

of alternating current and the armature 2 of motor 1. It will also be noted that the grid circuit of the tube 4 contains four sources of potential in series, namely, the alternating potential provided by potentiometer 32, the direct potential drop across the upper half of resistor 24, the direct potential provided by the biasing battery 25, and the direct potential drop across the upper half of resistor 13.

The drop across the resistor 24, as will be described later, is arranged to vary in polarity with the desired direction of rotation of the armature 2. The magnitude of the potential across resistor 24 may be made proportional to the magnitude of position change required in the driven object. The potential of the biasing battery 25 is fixed at a value sufficient to inhibit conduction through either tube when maximum anode voltage is applied and the system is at rest. The potential drop across resistor 13 is occasioned by the current flowing through it due to the back E. M. F. generated in the motor armature 2 by its rotation.

If, now, it be assumed that the motor 1 is at rest and that a potential is impressed across resistor 24 of sufficient magnitude and of such a polarity that the point 30 is positive and the point 31 is negative, the grid 20 will become positive with respect to its cathode, thereby permitting anode current to flow through the tube 4 and the armature 2 during the half cycles of anode potential or portions thereof in which the anode 11 is positive with respect to its cathode. The armature 2 being immersed in the continuous magnetic field provided by the winding 3 will therefore commence to rotate under the influence of the rectified current impulses flowing through it. As the armature increases its speed, it will generate a back E. M. F. which is exactly proportional to the armature speed and is available for control of the rectifier grid at all times when no current flows through the tube. This back E. M. F. being applied across the resistor 13, causes a current to flow through this resistor which thereby introduces a potential into the grid circuit of tube 4 which opposes the potential due to the drop across the upper half of resistor 24. When the back E. M. F. across the upper half of resistor 13 reaches a magnitude substantially equal to the potential drop across the upper half of resistor 24, the potential of grid 20 will automatically be varied to cause the discharge in each positive half cycle of anode potential to take place at the right instant in each cycle to prevent the motor from increasing or decreasing its speed beyond that which corresponds to the magnitude of the potential then existing across resistor 24. The motor speed is thereby accurately controlled. It should also be noted that when the polarity of the potential impressed across the resistance 24 is such as to make the point 30 positive, the point 31 is negative and the grid 21 of tube 5 becomes negative so that when the tube 4 is operating, the tube 5 remains inactive. Similarly, if the potential across resistance 24 be reversed so that the point 31 becomes positive and the point 30 negative, tube 5 will become active, causing the motor armature 2 to rotate in the reverse direction. The tube 4 then remains inactive.

If, after the motor has been running in one direction, it should be desired to stop it, the controlling potential across resistor 24 is reduced to zero, so that the bias battery 25 is effective to hold both grids to cut-off potential. However, should the reduction of the potential on resistor 24 be sudden and should the motor tend to con-

tinue rotation, the tube opposite to the one which was driving the motor will be made active by the E. M. F. generated by motor's motion, tending to reverse the motor. This action amounts to a form of dynamic braking which rapidly brings the motor to a stop.

Let us now consider the circuit for producing the necessary control voltage for the grids of the rectifiers 4 and 5. This circuit is shown in the upper portion of the drawing. It is arranged to impress a potential across the terminals 30 and 31 of the resistor 24 which has a polarity corresponding to the direction of the required displacement of the driven object and a magnitude which may be proportional to the magnitude of the desired displacement, or may reach a maximum value even for small required displacement of the driven object. To this end a handwheel 10 may be arranged to drive a pointer 34 which is mounted adjacent to a scale 35 in such a manner that by rotating the handwheel the pointer may be rotated into a position corresponding to the desired position of the driven object. The handwheel shaft is also connected mechanically to the rotor or polyphase winding 36 of a self-synchronous motor 37. The motor 37 is also provided with a single-phase winding 38 which is connected to a source of alternating current of a high frequency. By this I mean a frequency which is high compared to the 60 cycle frequency heretofore used, say approximately 1000 to 2000 cycles per second; but I prefer to use a frequency in the neighborhood of 1500 cycles per second. The rotor 36 is electrically connected in parallel with the rotor 39 of a similar self-synchronous motor 40 having a single-phase stator winding 41. The rotor 39 is mechanically connected to the driven object. When the rotor 36 is in the same angular position with respect to its stator winding 38 as the rotor 39 is with respect to its stator winding 41, there will be no voltage induced in the winding 41. On the other hand, when the rotor 36 is displaced relative to the rotor 39 there will be a voltage induced in the winding 41. The polarity or relative phase of this voltage depends upon the direction of the displacement and the magnitude of the voltage depends upon the magnitude of the displacement.

The winding 41 is connected across a center-tapped resistor 42 whose extremities are connected to the grids of two high vacuum three-electrode tubes 43 and 44. The cathodes of these tubes are connected together and to the movable contact 45 of a potentiometer resistance 46 whose extremities are connected across the same source of high frequency alternating potential mentioned above. The phase of the potential across resistance 46 is therefore the same as that across the winding 38. One end of the potentiometer resistance 46 is connected to the center tap of resistance 42 and the other end is connected to the common point 47 of the anode circuits of the tubes 43 and 44. The anodes of these tubes are connected to the point 47 through filters 48 and 49 which are of suitable value to filter out the rectified high frequency alternating component introduced by the potential drop across resistance 46. Each filter may comprise, for example, a resistance and a parallel connected condenser as shown. The anode circuit of tube 43 may thus be traced from the anode of the tube through the filter 48 to the terminal 47 through a portion of resistance 46 to movable contact 45 to the cathode of the tube. Similarly, the anode circuit of tube 44 may be traced from the anode

of the tube through the filter 43 to the terminal 47 through the resistance 48 to the movable contact 45 and to the cathode of the tube. Since the portion of resistance 48, which lies between the terminal 50 and contact 45, is in series with the grid of each of the tubes 43 and 44, it provides an alternating bias potential for the grids of these tubes. This potential is adjusted to be of such a value that anode current flows through both of the tubes even though there is zero voltage induced in the winding 41. It will be observed that the voltage induced in this winding by relative displacement between the two rotors 36 and 39 appears across the resistance 42 and adds or subtracts to the grid voltage of the tubes 43 and 44, depending upon the direction of the displacement. If the displacement is in one direction, the potential drop across resistance 42 will be out of phase with the bias voltage on one of the grids but in phase with the bias voltage on the other grid. One tube will therefore pass more current while the current of the other will be reduced. If the relative displacement of the two rotors 36 and 39 be in the opposite direction, the effect on the anode currents of the two rectifiers will, of course, be reversed.

The result of the anode current flow in the anode circuits of the two tubes 43 and 44 will be to produce a potential difference across the terminals of a center-tapped resistor 51 which is connected between the two anodes. The ends of the resistor 51 are also connected to the grids of two amplifying tubes 52 and 53 which may be operated as Class A amplifiers. The cathodes of the tubes 52 and 53 are connected together and to the movable contact 54 of a potentiometer resistance 55 which is connected across a source of direct potential. The negative terminal of the resistance 55 is connected to the center tap of resistance 51, and the positive terminal of the resistance 55 is connected to the center tap of a center-tapped resistor 56 whose extremities are connected to the anodes of the tubes 52 and 53, respectively. Any potential appearing across resistance 51 is thus amplified and will appear across resistance 56 and also across terminals 30 and 31 which lie in the grid circuit of the grid controlled gaseous rectifiers 4 and 5.

It will now be evident that when the position of the driven object corresponds to the position of the pointer 34 so that the position of rotor 36 with respect to its stator 38 corresponds to the position of rotor 39 with respect to its stator 41, no voltage will be produced across the winding 41 and equal currents will flow in the anode circuits of tubes 43 and 44. Since these currents are in opposite directions, there will be no voltage across the resistance 51 and therefore no voltage across the terminals 30 and 31. The motor 2 will therefore remain at rest. When, however, the hand-wheel 10 is rotated to set the pointer 34 into a position corresponding to a desired new position of the driven object, a voltage, corresponding in phase to the direction of the position change which was made, will appear across winding 41 and resistance 42, causing the anode currents of tubes 43 and 44 to change. A potential difference will therefore exist across resistance 51, which will correspond in polarity to the direction of the displacement of the pointer 34. This potential will be amplified by the tubes 52 and 53 and will appear across the terminals 30 and 31, causing either the rectifier 4 or 5 to energize the motor 2 and to rotate the driven object in the desired direction as above described. Rotation of

the driven object also rotates the rotor 39 to which it is mechanically connected, the rotation being in such a direction as to bring the rotor 39 into positional correspondence with the rotor 36 and thereby again reducing the voltage in the winding 41 to zero. Thus when the driven object reaches the desired position, the motor 2 will stop.

By the use of the above arrangement a tight coupling is obtained between motion of the hand-wheel 10 and motion of the driven object so that there is substantially no time lag between them.

The maximum voltage impressed across resistor 24 should preferably be substantially equal to the full-speed back E. M. F. of the motor impressed across resistor 13. While it is often convenient to have the motor operate at a speed proportional to the required displacement of the driven object, this need not always be the case. Where, for example, a high sensitivity is desired and consequent rapid follow-up action, it may be preferable to arrange the amplifying circuit so that full control voltage is impressed across resistor 24 even for small displacements between pointer 34 and the driven object.

I have found that the gaseous grid controlled rectifier circuit described above operates in this follow-up system most satisfactorily when the controlling potential impressed across resistor 24 is a substantially pure direct potential without alternating components. It is necessary, therefore, to provide a suitable filter, as above described, to remove any alternating components which may otherwise be present. However, when filters are introduced into a follow-up system there is likewise inevitably introduced a time delay between the motion of the driven object and the motion of the controlling indicator. Where sensitivity and rapidity of response of the controlled object to motions of the controlling device are required, such time lag is, of course, objectionable, for it causes the system to act as though an elastic coupling member had been introduced between the controlling and the controlled mechanisms. According to my invention, however, such elasticity is substantially entirely eliminated because of the fact that I use a high frequency in the self-synchronous motor circuit for the production of the controlling potentials. Filters for such high frequencies can readily be constructed which substantially eliminate the high frequency components from the control voltage output circuit and which at the same time have only a negligible time constant.

Having now described my invention, I claim:

1. In a follow-up system for driving an object into positional agreement with a controlling object, a power motor for said driven object, a grid-controlled rectifier circuit for supplying power to said motor in one direction or the other in response to a direct potential which varies in polarity in accordance with the direction of positional disagreement between said objects and means for generating said potential comprising a self-synchronous transmitter motor having a stator winding energized by alternating current of a high frequency above approximately 1000 cycles per second and a rotor winding adapted to be rotated by the operator into a position corresponding to the desired position of the driven object, a self-synchronous receiver motor having rotor electrically connected in parallel with that of the transmitter and mechanically connected to the driven object and a stator winding adapted to have a voltage induced in it upon positional disagree-

ment between the two rotors and their respective stators, said voltage having an instantaneous polarity corresponding to the direction of said disagreement, rectifying means, means impressing said induced voltage on said rectifying means, the latter being adapted to produce a direct potential having a polarity corresponding to the direction of said disagreement and containing an alternating component of said high frequency, a filter for removing said high frequency component and means for impressing the resulting rectified and filtered voltage upon said grid-controlled rectifier circuit.

2. In a follow-up system for driving an object into positional agreement with a controlling object, a power motor for said driven object, a grid-controlled rectifier circuit for supplying power to said motor in one direction or the other in response to a direct potential which varies in polarity and magnitude in accordance with the direction and magnitude of positional disagreement between said objects and means for generating said potential comprising a self-synchronous transmitter motor having a stator winding energized by alternating current of a high frequency above approximately 1000 cycles per second and a rotor winding adapted to be rotated by the operator into a position corresponding to the desired position of the driven object, a self-synchronous receiver motor having a rotor electrically connected in parallel with that of the transmitter and mechanically connected to the driven object and a stator winding adapted to have a voltage induced in it upon positional disagreement between the two rotors and their respective stators, said voltage having an instantaneous polarity and a magnitude corresponding to the direction and magnitude of said disagreement, rectifying means, means impressing said induced voltage on said rectifying means, the latter being adapted to produce a direct potential having a polarity and magnitude corresponding to said direction and magnitude of said disagreement and containing an alternating component of said high frequency, a filter for removing said high frequency component and means for impressing the resulting rectified and filtered voltage upon said grid-controlled rectifier circuit.

3. In a follow-up system for driving an object into positional agreement with a controlling object, a power motor for said driven object, a grid-controlled rectifier circuit for supplying power to said motor in one direction or the other in response to a direct potential which varies in polarity in accordance with the direction of positional disagreement between said objects and means for generating said potential comprising a self-synchronous transmitter motor having a stator winding energized by alternating current of a high frequency of approximately 1500 cycles per second and a rotor winding adapted to be rotated by the operator into a position corresponding to the desired position of the driven object, a self-synchronous receiver motor having rotor electrically connected in parallel with that of the transmitter and mechanically connected to the driven object and a stator winding adapted to have a voltage induced in it upon positional disagreement between the two rotors and their respective stators, said voltage having an instantaneous polarity corresponding to the direction of said disagreement, rectifying means, means impressing said induced voltage on said rectifying means, the latter being adapted to produce a direct potential having a polarity corresponding to

the direction of said disagreement and containing an alternating component of said high frequency, a filter for removing said high frequency component and means for impressing the resulting rectified and filtered voltage upon said grid-controlled rectifier circuit.

4. In a follow-up system for driving an object into positional agreement with a controlling object, means for producing a direct potential varying in polarity and magnitude in accordance with the direction and magnitude of positional disagreement between said objects comprising self-synchronous transmitter and receiver system, means exciting the same with alternating current of a high frequency above approximately 1000 cycles per second, means mechanically connecting said system with said controlling object and said driven object for producing an alternating potential of said high frequency having a magnitude and an instantaneous polarity corresponding to the magnitude and direction of said positional disagreement, rectifying means for said high frequency potential adapted to produce a direct potential having a polarity and a magnitude corresponding to the direction and magnitude of said positional disagreement, and having an alternating component of said high frequency, and a filter for removing said high frequency component.

5. In a follow-up system for driving an object into positional agreement with a controlling object, means for producing a direct potential varying in polarity and magnitude in accordance with the direction and magnitude of positional disagreement between said objects comprising self-synchronous transmitter and receiver system, means exciting the same with alternating current of a high frequency above approximately 1000 cycles per second, means mechanically connecting said system with said controlling object and said driven object for producing an alternating potential of said high frequency having a magnitude and an instantaneous polarity corresponding to the magnitude and direction of said positional disagreement, rectifying means for said high frequency potential comprising a pair of oppositely connected vacuum tube rectifiers having cathode, anode and grid electrodes, a source of anode potential for said tubes, means connecting said tubes in opposite relation to each other, means impressing a derivative of said high frequency potential upon the grids of said tubes in opposite instantaneous polarity, means biasing both of said grids with an alternating potential of said high frequency of the same phase as the potential of said self-synchronous system exciting current and of a magnitude to cause both tubes normally to pass current, whereby for one instantaneous polarity of said produced potential the current passed by one tube will increase and the current passed by the other tube will diminish and vice versa for the opposite instantaneous polarity of said produced potential, means in the anode circuit of each tube for separately filtering out the high frequency alternating component, means opposing the filtered rectified outputs of the two tubes, means deriving a resultant potential corresponding to said outputs and means responsive to said resultant potential for altering the position of said driven object to remove said positional disagreement.

6. In a follow-up system for driving an object into positional agreement with a controlling object, means for producing a direct potential varying in polarity and magnitude in accordance

with the direction and magnitude of positional disagreement between said objects comprising self-synchronous transmitter and receiver system, means exciting the same with alternating current of a high frequency above approximately 1000 cycles per second, means mechanically connecting said system with said controlling object and said driving object for producing an alternating potential of said high frequency having a magnitude and an instantaneous polarity corresponding to the magnitude and direction of said positional disagreement, rectifying means for said high frequency potential comprising a pair of oppositely connected vacuum tube rectifiers having cathode, anode and grid electrodes, a source of anode potential for said tubes, means connecting said tubes in opposite relation to each other, means impressing a derivative of said high frequency potential upon the grids of said tubes in opposite instantaneous polarity, means biasing both of said grids with an alternating potential of said high frequency of the same phase as the potential of said self-synchronous system exciting current and of a magnitude to cause both tubes normally to pass current, whereby for one instantaneous polarity of said produced potential the current passed by one tube will increase and the current passed by the other will diminish and vice versa for the opposite instantaneous polarity of said produced potential, means in the anode circuit of each tube for separately filtering out the high frequency alternating component, a resistor connected between the anodes of the two tubes so that a direct current will flow through said resistor which is the resultant of the opposed rectified and filtered outputs of the two tubes and means responsive to the polarity and magnitude of the resulting potential drop across said resistor for altering the position of said driven object to remove said positional disagreement.

7. In a follow-up system for driving an object into positional agreement with a controlling object, means for producing a direct potential varying in polarity and magnitude in accordance with the direction and magnitude of positional disagreement between said objects comprising self-synchronous transmitter and receiver system, means exciting the same with alternating current of a high frequency above approximately 1000 cycles per second, means mechanically connecting said system with said controlling object and said driven object for producing an alternating potential of said high frequency having a magnitude and an instantaneous polarity corresponding to the magnitude and direction of said positional disagreement, rectifying means for said high frequency potential comprising a pair of oppositely connected vacuum tube rectifiers having cathode, anode and grid electrodes, means connecting said tubes in opposite relation to each other, means impressing a derivative of said high frequency potential of the same phase as the potential of said self-synchronous system exciting current upon the anodes of said tubes in the same instantaneous polarity, means biasing both of said grids with an alternating potential of said high frequency and of instantaneous polarity and magnitude to cause both tubes normally to pass current, and means impressing a derivative of said produced high frequency potential upon the grids of said tubes in opposite instantaneous polarity, whereby for one instantaneous polarity of said produced potential the current passed by one tube will increase and the current passed by the other

tube will diminish and vice versa for the opposite instantaneous polarity of said produced potential, means in the anode circuit of each tube for separately filtering out the high frequency alternating component, means opposing the filtered rectified outputs of the two tubes, means deriving a resultant potential corresponding to said outputs and means responsive to said resultant potential for altering the position of said driven object to remove said positional disagreement.

8. In a follow-up system for driving an object into positional agreement with a controlling object, means for producing a direct potential varying in polarity and magnitude in accordance with the direction and magnitude of positional disagreement between said objects comprising self-synchronous transmitter and receiver system, means exciting the same with alternating current of a high frequency above approximately 1000 cycles per second, means mechanically connecting said system with said controlling object and said driving object for producing an alternating potential of said high frequency having a magnitude and an instantaneous polarity corresponding to the magnitude and direction of said positional disagreement, rectifying means for said high frequency potential comprising a pair of oppositely connected vacuum tube rectifiers having cathode, anode and grid electrodes, means connecting said tubes in opposite relation to each other, means impressing a derivative of said high frequency potential of the same phase as the potential of said self-synchronous system exciting current upon the anodes of said tubes in the same instantaneous polarity, means biasing both of said grids with an alternating potential of said high frequency and of instantaneous polarity and magnitude to cause both tubes normally to pass current, and means impressing a derivative of said high frequency potential upon the grids of said tubes in opposite instantaneous polarity, whereby for one instantaneous polarity of said produced potential the current passed by one tube will increase and the current passed by the other will diminish and vice versa for the opposite instantaneous polarity of said produced potential, means in the anode circuit of each tube for separately filtering out the high frequency alternating component, a resistor connected between the anodes of the two tubes so that a direct current will flow through said resistor which is the resultant of the opposed rectified and filtered outputs of the two tubes and means responsive to the polarity and magnitude of the resulting potential drop across said resistor for altering the position of said driven object to remove said positional disagreement.

9. In a follow-up system for driving an object into positional agreement with a controlling object, a self-synchronous transmitter and receiver system, means energizing the same with alternating current of a high frequency above approximately 1000 cycles per second, rectifier and filter means operatively associated with said system for delivering a direct current, said filter being adapted to remove alternating current components having a frequency not substantially less than said high frequency, motor means for driving said object and means for energizing said motor, said energizing means being adapted to be activated by said direct current, whereby time lag between operation of said self-synchronous system and said motor is reduced.

10. In a follow-up system for driving an object into positional agreement with a controlling

object, a self-synchronous transmitter and receiver system, means energizing the same with alternating current of a high frequency above approximately 1000 cycles per second, rectifier and filter means operatively associated with said system for delivering a controlling direct current, said filter being adapted to remove alternating current components having a frequency

not substantially less than said high frequency, a motor and a source of rectified alternating current of relatively low frequency for operating the same, said source having grid control means to which said controlling direct current is applied, whereby time lag between operation of said self-synchronous system and said motor is reduced.

HOWARD A. SATTERLEE.
